UNITED STATES PATENT OFFICE.

ARTHUR G. MCKEE, OF CLEVELAND, OHIO.

DOWNCOMER.

1,293,839.

Specification of Letters Patent. Patented Feb. 11, 1919.

Application filed May 5, 1917. Serial No. 166,702.

To all whom it may concern:

Be it known that I, ARTHUR G. MCKEE, a citizen of the United States, resident of Cleveland, county of Cuyahoga, and State 5 of Ohio, have invented new and useful Improvements in Downcomers, of which the following is a specification, the principle of the invention being herein explained and the best mode in which I have contemplated 10 applying that principle, so as to distinguish it from other inventions.

My invention relates to furnace constructions and particularly to the construction of the downcomers thereof. More particularly, my invention relates to such a construction of the downcomers as will provide means for preventing much of the heavy material, such as coke and limestone and the coarse particles of ore, being carried off 20 from the furnace with the gases, thus preventing the escape of much of the material whose loss would cause the furnace to become cold when it "slips" and also obviating much of the cleaning which must be done 25 in the dust collector. Means are provided whereby the material is trapped and then returned by gravity to the furnace.

The annexed drawing and the following description set forth in detail certain means 30 embodying my invention, the disclosed means, however, constituting but one of various mechanical forms in which the principle of the invention may be employed.

In said annexed drawing:

Figure 1 represents a vertical axial section through my improved downcomer, showing the same in relation to a furnace top; Fig. 2 is a vertical section and elevation taken in the planes indicated by the 40 lines 2-2 and II-II, Fig. 1; and Fig. 3 is a horizontal section taken in the plane indicated by the lines 3-3, Fig. 1.

Referring to the annexed drawing, a suggestion of a furnace top is shown at 1 to 45 which is connected by a collar 2 my improved downcomer consisting of an upwardly extending construction comprising a steep sloping outlet 3-4 from the furnace and an upwardly extending outlet 4' from member 4; a downwardly extending part comprising a filler 7 and a conductor 8 leading to the dust collector; and intermediate connections comprising a T 5 and an elbow 6. It will be noticed that the upwardly extending outlet 4' intersects the 50 main wall 4³ of the member 4 below the

upper end thereof and at an obtuse angle so that a passage X-X greater in area than the normal area Y-Y of the downcomer passage is provided between said member 4 and said outlet 4' as also a pocket 60 adjacently to said upper end and back of a baffling member, hereinafter mentioned, out of the current of the issuing gases. The members 4 and 4' might as well be so constructed as to extend the area designated by X-X up to the head 12, hereinafter mentioned, in which event the upper wall of the pocket would be a plainer surface. A portion 70 of said enlarged area X-X is, however, cut off from the pathway of the gases through the downcomer by means of a deflector or baffling member 9 suspended within the upper part of the outlet 4' by means of a flange 9' disposed between an upper 75 flange 4² of the outlet 4', and a lower flange 5' of the T 5, said flanges 4² and 5' being secured together by bolts 10 outside of the periphery of flange 9'. Said deflector 9 is of the construction shown plainly in the 80 annexed drawing, being formed, in addition to the flange 9', with lateral edges 9² disposed substantially parallel with the wall of the outlet 4', and with a bottom edge 9³ of the half elliptical shape shown in Fig. 85 3, whereby the deflector 9 restricts the effective area of the passage X-X between the members 4 and 4' to about the average area Y-Y of the downcomer passage or to about the area of the passage Z-Z through 90 the top of the deflector 9. Heads 11 and 12, respectively, for closing the top of the T 5 and the upper end of the member 4 are provided, as plainly shown in Fig. 1.

It is apparent from the foregoing description that the heavy particles such as coke and limestone and the coarse particles of ore carried by the gases discharged from the furnace and which do not turn short enough to go into the outlet 4', and are carried past the bottom of deflector 9, will be projected against the head 12 of the member 4 and in back of the baffling member or deflector 9 out of the gas current and will drop to the bottom of the sloping member 105 4 and by gravity will slide down to the bottom of the outlet 3-4 back into the furnace. Some part of the lighter solid materials, such as considerable of the ore will, of course, be carried off with the gases but for 110 the most part the solid material, especially the coke and limestone and the large parti-

cles of ore will be baffled and detrained in the manner hereinbefore described, and carried back into the furnace.

The improved construction shown and described has worked out extremely well in practice, so that when the furnace "slips", an occurrence which has usually resulted in the furnace becoming cold, it is now found to be hot and limy which is a highly favorable condition and shows that this construction, while it does not catch any considerable quantity of the fine ore, does prevent loss of coke and limestone, which are normally coarser than the ore, and the large particles of ore, by intercepting them in their exit from the furnace and returning them quickly thereto.

What I claim is:

1. The combination with a furnace; of a 20 downcomer construction comprising an inclined upward portion from the furnace and a portion bent sharply upwardly intersecting said inclined portion, the communicating opening between said two portions being 25 spaced from the top of said inclined portion, the latter being closed except for its communicating openings with the furnace, and with said sharply upwardly bent portion, whereby particles detrained in said space 30 and falling to the floor of said inclined portion will be returned to the furnace.
2. The combination with a furnace; of a 35 downcomer construction comprising an inclined upward outlet from the furnace provided with a closed upper end and an outlet bent sharply upwardly intersecting said first-mentioned outlet, a pocket, open to said inclined outlet and thence into the furnace, into which heavier particles are projected 40 being provided intermediately said closed end and the intersection of said outlets.
3. The combination with a furnace top; of a 45 downcomer construction comprising a steep upward outlet from said top formed with a sharp bend, and means disposed in said outlet adjacently to said bend adapted to detrain particles from the passing gases to the inclined floor of the outlet whence they are returned to the furnace.
- 50 4. The combination with the furnace; of a downcomer construction comprising a sloping outlet from the furnace, an upwardly extending outlet from said sloping outlet, and a baffle partially closing said last-named outlet.
- 55 5. The combination with the furnace; of a downcomer construction comprising a sloping outlet from the furnace, an upwardly extending outlet from said sloping outlet and of a cross-sectional area larger than said

first-mentioned outlet, and a baffle disposed within said last-mentioned outlet and restricting the cross-sectional area thereof to substantially that of said sloping outlet.

6. The combination with a furnace; of a 65 downcomer construction comprising a steep outlet from the furnace, a baffle partially closing said outlet, and means forming a pocket adjacently to said baffle, the construction being such that heavier particles are detrained by said baffle into said pocket, whence they are returned to the furnace.

7. The combination with a furnace; of a 75 downcomer construction comprising a steep portion from the furnace, an upwardly extending portion intersecting said first-mentioned portion, the construction being such that a communicating opening therebetween of cross-sectional area larger than that of said first-mentioned portion is created, and 80 a baffle disposed within said last-mentioned portion and restricting the effective cross-sectional area of said opening to substantially that of said first-mentioned portion.

8. The combination with the furnace; of a 85 downcomer construction comprising a steep portion adjacent to the furnace, a portion bent sharply upwardly, a deflector, and a pocket formed adjacently to the upper end of said steep portion and back of said deflector to receive detrained particles and return them to the furnace.

9. The combination with the furnace; of a 95 downcomer construction comprising a sloping outlet from the furnace provided with a closed upper end, an upwardly extending outlet from said sloping outlet located below said closed end, and a baffle partially closing said upwardly extending outlet, a pocket into which heavier particles are projected 100 thus being formed back of said baffle and in said sloping outlet beyond the vertical plane intersecting the bottom of said baffle.

10. In constructions of the character described, an element comprising an annular 105 suspending member formed integrally with a downwardly projecting, inwardly inclined baffling surface.

11. In constructions of the character described, a deflecting element comprising a 110 downwardly projecting, inwardly inclined curved wall formed with vertical side edges.

12. In constructions of the character described, a deflecting element comprising a downwardly projecting, inwardly inclined 115 curved wall formed with side edges and a half elliptical bottom edge.

Signed by me, this 21st day of April, 1917.

ARTHUR G. MCKEE.
